(57) **CLAIM**

The ornamental design for a cover plate for a computing device, as shown and described.

DESCRIPTION

FIG. 1 is a front view of a cover plate for a computing device; FIG. 2 is a top view of the cover plate for a computing device; and,

FIG. 3 is a bottom view of the cover plate for a computing device.

The broken lines showing of various regions and the unshaded areas therein are for the purpose of illustrating the article and form no part of the claimed design.

1 Claim, 3 Drawing Sheets

FIG. 1

FIG. 2

FIG. 3
